RADIO OR LIKE RECEIVER

Arthur Wallace Edwards, Hollinwood, England,
assignor to Ferranti Electric Inc., New York,
N. Y.

Application December 4, 1936, Serial No. 114,272
In Great Britain December 7, 1935

6 Claims. (Cl. 250—26)

This invention relates to radio or like receivers of the type incorporating one or more band-pass filter stages such as, for instance, an intermediate frequency stage of a superheterodyne receiver.

In receivers of this type, the wider the frequency band passed through the receiver, the better is the fidelity of the reproduction to the transmission being received. In order to permit the passage of a wide frequency band the response curve of each band-pass filter stage should be of the double hump form; the width of frequency band that can be passed for any given transmission being received differs according to the strength of the transmission, and consequently the shape of the response curve also differs. It is well known that tuning of receivers under conditions of a wide response curve is difficult owing to there being a number of positions of the tuning apparatus for which apparently similar results are obtained.

It is desirable therefore to narrow the frequency band passed through the receiver to correspond with a response curve having a single peak before performing the tuning operation, 25 after which process the band width passed is increased to suit the transmission being received.

To effect this procedure it has been proposed to provide manual means for ensuring that before the receiver can be tuned to the required transmission and the coupling between the coils then increased in order to widen the frequency band passed through the receiver, the coupling between the two members of each band-pass filter stage must be decreased, with the result that the response curve of the filter is caused to be of the single peak form.

The object of this invention is to provide improved or simplified means for achieving such result.

The invention consists in a radio or like receiver incorporating features set out in the claims appended hereto.

Referring to the accompanying diagrammatic drawings:—

Figure 1 is a perspective view of part of a tuning apparatus embodying the present invention in one form.

Figure 2 is an enlarged side view of the intermediate frequency transformer coils and mounting thereof with part of the enclosing case broken away.

Figures 3 and 4 are enlarged end views of part of the tuning and fidelity control mechanism.

Figure 5 is an enlarged side view of said part 55 of the mechanism.

Figure 6 is an enlarged side view of part of the coil operating mechanism.

Figure 7 is an enlarged end view of said part of the coil operating mechanism, and

Figure 8 is an enlarged plan view of said part of the coil operating mechanism.

In carrying the invention into effect according to the form illustrated by way of example as applied to a superheterodyne radio receiver, I construct the intermediate frequency transformer in such a manner as to have its two coils *a*, *b* mounted coaxially, the coil *a* being fixed rigidly to a tubular member *c* and the coil *b* being mounted upon a sleeve *d* capable of movement in an axial direction along the tube *c*. 15

A tube *f* is slideable within the tube *c* and carries a radial pin *g* by which the tubes *d* and *f* are constrained to move together as one in a vertical direction; vertical slots *h* in the tube *c* through which the pin *g* passes are provided to present 20 this vertical movement. A cranked rod *e* is pivoted to the tube *f* and to a slotted plate *j* and is carried in fixed forks *k* whereby rotation of a shaft *t* carrying an arm *q* with a pin *m* engaging the slot *n* in the plate *j* effects a rise or fall 25 of the coil *b*. The shaft *t* is coupled to a shaft *o* passing through the front of the cabinet (not shown) containing the receiver, a knob *p* being attached to the shaft *o*.

Associated with the shaft *o* is a fidelity control device which comprises a notched wheel *r* mounted frictionally on the shaft, being held by means of a spring washer or the like (not shown). The degree of friction is such that when the notched wheel *r* is held, a spring *u* tending to 30 rotate the shaft *t* in a counterclockwise direction in Figures 3 and 4 is unable to rotate the shaft.

Two pins or fingers *v*, *v'* attached rigidly to or forming part of the lower ends of two approximately diametrically opposite arms *w*, *x* co-operate with the notched wheel *r* in such a manner that when one pin or finger *v*, *v'* is in engagement with the wheel *r*, the other bears against the periphery of the wheel between two adjacent notches. The two arms *w*, *x* are pivoted to each other at the mid-point of each. A cam *s* is provided in driving relationship with the shaft and adjacent to the notched wheel *r*; this cam has two approximately diametrically opposite lifts *y*, *z*, the lift *z* being provided with a stop *2* at the top thereof. The fingers follow the cam whenever the latter rotates, riding up the lifts until the stop prevents further rotation of the cam. A subsidiary spring *3* is disposed on the pivot 45 50 55

between the two arms so as to urge both fingers v , v' towards the notched wheel r .

The tuning apparatus includes a spindle 5 which latter is mounted parallel to the shaft o . 5 A star wheel 6 is fixed rigidly on this spindle. Two studs 7, 8, one attached to each of the remote ends of the two arms referred to above, co-operate with the star wheel 6 in such a manner that in the position shown in Figure 3 the arm 10 x engaged by the finger v' with the notched wheel r is also engaged by a stud with the star wheel 6, the other arm w being held out of engagement with the notched wheel r by the pin 8 engaging the star wheel 6.

15 In operation, assuming the receiver to have been tuned to a particular station and the coupling between the coils a , b of the intermediate frequency transformer to have been adjusted to give a response curve suited to the station in question; upon rotating the tuning spindle 5, with the object of effecting a change in the station being received, the star wheel 6 rotates therewith and on the first movement the pin 7 which is in engagement with it is forced outwards so that the finger 20 v' on the opposite end of the arm x to which the pin 7 is attached is lifted out of engagement with the notched wheel r . Thus the notched wheel is no longer held and the spring u causes the shafts 25 t , o to rotate into the position shown in Figure 1 and the movable coil b of the intermediate frequency transformer to move towards its lowermost position.

30 The cam s on the shaft o rotates with the shaft sufficiently for the two swell portions y , z to lift 35 and retain the two fingers v , v' out of contact with the notched wheel r , thus simultaneously preventing the pins 7, 8 on the opposite ends of the arms from contacting or re-engaging with the star wheel 6.

35 The mechanism now occupies the position 40 shown in Figure 4. The tuning spindle 5 is now free to be rotated without actuating the arms w , x and it may be adjusted into any desired position.

45 When the receiver has been retuned to the desired station, the operator turns the knob p attached to the shaft o in order to move the movable coil b nearer to the fixed coil a until the coupling is such as to give a response curve suited to the new station. This operation rotates the 50 cam s in clockwise direction and allows the fingers to drop from the swells or lifts of the cam to contact with the notched wheel r , e. g. as shown in Figure 3.

55 As soon as one or other of the two fingers engages with the notched wheel the latter is arrested and the pins 7, 8 are brought into operative engagement with the star wheel 6 ready for the next retuning process, but the knob p may be moved to vary as desired the position of the moving coil b since the notched wheel r remains 60 locked.

65 The teeth of the notched wheel r are so shaped as to ensure that one or other finger v , v' will drop into a notch.

70 The stop 2 on the cam s may be employed as an audible indicating device, the sound caused when it strikes the finger v' acting as an indication to the operator that the receiver is in its high selectivity condition.

75 The arrangement described for enabling rotation of the shafts to effect movement of the coil on the intermediate frequency transformer is by way of example only and does not form part of the invention.

Having now described my invention what I claim as new and desire to secure by Letters Patent is:—

1. A receiver incorporating an adjustable band-pass filter circuit, a tuning control device, means actuated by mere rotation for tuning purposes of said tuning control device automatically reducing to a pre-set minimum the frequency range of responsiveness of said band-pass filter circuit and a further control device for subsequently increasing to any desired extent the frequency range of response. 10

2. A receiver as claimed in claim 1 wherein the said band-pass filter circuit includes relatively movable members for varying the degree 15 of coupling and in addition there is provided as part of said means actuated by mere rotation of said tuning control device a return spring for urging the said members to adopt a position corresponding to minimum frequency range of responsiveness of 20 said band-pass filter circuit, retaining means for preventing the said members from responding to the action of the said return spring and further means associated with said tuning control device operable to release said retaining means upon variation of the position of 25 said tuning control device.

3. A receiver as claimed in claim 1 wherein the said band-pass filter circuit includes relatively movable members for varying the degree 30 of coupling, there is provided as part of said means actuated by mere rotation of said tuning control device a return spring for urging said members to adopt a position corresponding to minimum frequency range of responsiveness of 35 said band-pass filter circuit, retaining means for preventing the said members from responding to the action of said return spring, and further means associated with said tuning control device operable to release said retaining means upon variation of the position of 40 said tuning control device and wherein said retaining means include a notched wheel mounted frictionally on a shaft 45 operatively associated with said relatively movable members and two arms are provided having a finger on one end of each arm, the fingers being urged into engagement with said notched wheel by the action of a subsidiary spring, the arrangement being such that when one of the pins engages a notch the other contacts with a tooth. 50

4. A receiver as claimed in claim 1 having relatively movable members for varying the degree of coupling in said band-pass filter circuit and wherein said means actuated by mere rotation of said tuning control device include a return spring for said members, retaining means for said members, releasing means for said retaining means operable by said tuning control device, said retaining means including a notched wheel mounted frictionally on a shaft operatively associated with said relatively movable members, two arms having a finger on one end of each, the fingers being urged into engagement with said notched wheel by a subsidiary spring, said releasing means associated with said tuning control device serving to release a finger from engagement with said notched wheel, and a cam serving to prevent engagement or re-engagement between the fingers and the notched wheel upon rotation of said shaft having been effected by said return spring. 55 60 65

5. A receiver as claimed in claim 1 including as part of said means actuated by mere rotation of said tuning control device a cam, a pair of arms having fingers at both ends of each, a 70 75

notched wheel associated with one pair of fingers, a star wheel associated with the other pair of fingers, a cam associated with said notched wheel, a part on said cam co-operating with a stop and a return spring for urging said part of the cam into engagement with the stop.

5. A receiver including in combination an adjustable band-pass filter circuit having two relatively movable members for varying the degree 10 of coupling, a return spring for urging said members into a position corresponding to minimum frequency range of responsiveness of said band-pass filter circuit, a tuning control device, a

fidelity control shaft associated with said relatively movable members, a notched wheel on said shaft, a star wheel associated with said tuning control device, a pair of arms having fingers on both ends of each, the fingers on the opposite ends of one arm simultaneously respectively lying between a pair of teeth on the star wheel and engaging a notch in the notched wheel whilst the fingers on the opposite ends of the other arm simultaneously respectively rest upon the extremity of a star wheel tooth and a notched wheel tooth.

10 ARTHUR WALLACE EDWARDS.
